(57) **CLAIM**

The ornamental design for a CD cleaner, as shown and described.

DESCRIPTION

FIG. 1 is a perspective view of a CD cleaner; FIG. 2 is a top plan view of the CD cleaner of FIG. 1; FIG. 3 is a bottom plan view of the CD cleaner of FIG. 1; FIG. 4 is a left side elevational view of the CD cleaner of FIG. 1;

FIG. 5 is a right side elevational view of the CD cleaner of FIG. 1;

FIG. 6 is a front elevational view of the CD cleaner of FIG. 1; and,

FIG. 7 is a rear elevational view of the CD cleaner of FIG. 1.

The broken-line structure shown in FIG. 1 is for illustrative purposes only and forms no part of the claimed design.
